UNITED STATES PATENT OFFICE.

ARTHUR C. CROFT, OF KANSAS CITY, MISSOURI.

SHIPPING AND DISPLAYING BOX.

Application filed November 19, 1924. Serial No. 750,932.

To all whom it may concern:

Be it known that I, ARTHUR C. CROFT, a citizen of the United States, residing at Kansas City, in the county of Jackson and State of Missouri, have invented a new and useful Shipping and Displaying Box, of which the following is a specification.

My invention relates to shipping and displaying boxes, and particularly to an improvement of this character for which I have applied for a patent therefor, Serial No. 731,465.

The object of the invention is to provide a box for shipping and displaying chocolates and candies and provided with facilities for holding separated individual candies or other fragile articles to prevent breaking or crushing of the same when packing, transporting, or handling the box.

A further object of the invention is to arrange the individual chocolates or candies in individual order with respect to the various flavors thereof and to provide facilities for selection of the candies without handling the same.

I attain these objects and other advantages by means of the structure and combination of parts illustrated in the accompanying drawing in which—Figure 1, is a top plan view of the box embodying my invention, the cover being omitted to disclose the separator device and the carrier associated therewith. Figure 2, is a longitudinal section of the box, on the line 2—2, in Figure 1. Figure 3, is a top plan view of one of the carriers, and showing indentations therein for folding the carrier to shape and, Figure 4, is a cross section of the box and its cover, and showing the separator and carrier associated therewith.

Similar numerals of reference refer to corresponding parts throughout the several views.

Referring to the drawings—the numeral 1, designates a shipping and displaying box constructed in accordance with my invention and which is made of any suitable flexible material, preferably card board and 2, indicates the box cover. A separator device 3, is stationed in the box, at a point intermediate of the depth thereof, and disposed in a horizontal plane. The separator may be held in place by any suitable means, preferably by a supporting flange, as shown in Figure 2.

The separator 3, consists of a plate of

flexible board having therein methodically arranged openings 4, preferably arranged in rows to thereby provide between the ends of the openings transverse strips 5, which are adapted for supporting a carrier device hereinafter more particularly described and, between the sides of the openings, longitudinally extending strips 6, which are adapted for separating individual candies in the individual openings and, at the same time, providing spaces 7, at the openings upon which may be marked information data respecting the quality or flavor of the individual candies located in the openings in the separator, as shown at 8, in Figure 1. Associated with the separator is a strip 9, of suitable flexible material, preferably card board, and having transversely extending rows of indentations 20, indicating the points of folding or shaping the strips to form pockets 10, adapted to be suspended in the openings 4, in the separator and from the strips 5, to receive and carry therein chocolates, candy, or fragile articles, in trays or wrappers 12, as shown in Figures 1 and 2, and also to form of the end portions of the strip 9, upturned flanges, as shown in Figure 2. The strip 9, when folded in conformity to the transverse indented lines thereon, forms a carrier 14, adapted for hanging from the strips 5, and suspend therefrom the pockets 10, into the lower portion of the box.

When chocolates or candies are to be packed into the box, a separator device is selected and a strip 9, is folded to conform to the indented lines 20, and then placed in one of the rows of openings in the separator, in such a manner that the carrier formed by the folding of the strip, will be suspended from the strips 5, between the ends of the openings, the pockets of the carrier depending in the openings. A strip 9, is manipulated as described for each row of openings in the separator and, when the separator is fully equipped with carriers, the same is placed in the box in a horizontal plane and the end portions or flanges of the carriers are turned upward so that the edges are positioned against the lower side of the separator and the flanges bearing against the inner side of the box. The reaction of the flanges effecting a frictional bearing on the box, both the separator and the carrier associated therewith are held in place and, both being made of flexible material, they are resilient in

considerable degree and absorb shocks sustained by the box, yielding and rebounding in the well known manner.

After the separator and carriers have been 5 mounted in the box, chocolates or candy are individually placed in the trays or wrappers 12, and the individual article deposited in the pockets 10, in the carriers, the wrapper or tray extending above the article a 10 suitable distance, to and above the separator. The individual pieces of chocolate or candy may be arranged in the pocket 10, at the point where its particular quality or flavor is marked on the spaces 7, on the strips 15 6, this arrangement making it possible to make a selection of a particular flavor without handling the candies to locate the candy wanted. The flexible resilient pockets of the carriers provide means for the safe and 20 sanitary packing, shipping, displaying, and selection of chocolates or candy, and the segregation of the individual pieces of the contents of the box prevents contact with each other. The resilient carriers function, 25 also, to absorb shock and vibration incident to transportation and handling of the box. The information data marked at the pocket openings permits the identification of the chocolate or candy having the flavor de- 30 sired without handling the contents of the box for the purpose.

Having described my invention what I claim is—

1. In a shipping and displaying box, the combination with the box, of a plate of flexible resilient material mounted intermediate of the depth of the inside of the box and provided with individual series of pocket openings therein, and individual strips of flexible resilient material associated with 40 said plate and manipulated thereon to form individual pockets depending in the box through the pocket openings in the plate and adapted for segregating individually the contents of the box. 45

2. In a shipping and displaying box, the combination with the box, of a plate of flexible resilient material mounted intermediate of the depth of the inside of the box and provided with individual series of pocket 50 openings therein, said plate bearing at the pocket openings therein information data relative to the article in the pocket openings, and individual strips of flexible resilient material associated with said plate and manipulated thereon to form individual pockets depending in the box through the pocket 55 openings in the plate and adapted for segregating individually the contents of the box.

Dated Kansas City, Missouri, October 60
31st, 1924.

ARTHUR C. CROFT.
